UNITED STATES PATENT OFFICE.

ALVIN HAYES, OF MEDINA, OHIO.

COMBINED HARROW AND ROLLER.

No. 884,658.

Specification of Letters Patent. Patented April 14, 1908.

Application filed December 17, 1907. Serial No. 406,847.

To all whom it may concern:

Be it known that I, ALVIN HAYES, a citizen of the United States, residing at Medina, in the county of Medina and State of Ohio, have invented certain new and useful Improvements in Combined Harrows and Rollers, of which the following is a specification, reference being had to the accompanying drawings.

10 My invention relates to improvements in combined harrows and rollers; and an object of my invention is to provide a device of this character which will be simple in construction, cheap in manufacture and efficient in 15 operation.

Another object of my invention is to provide a device of this character with load-supports which may be adjusted along the frame to vary the point of application of the load.

20 In the drawings illustrating the principle of my invention and the best mode now known to me of applying that principle, Figure 1 is a plan of my new combined harrow and roller; Fig. 2 is a side elevation thereof; 25 Fig. 3 is a section on line A—A looking in the direction of the arrow; and Fig. 4 is a sectional detail illustrating the mode of connection of the load supports to the frame.

In my new combined harrow and roller, 30 the frame is very simple consisting of two side-bars *a* in which is journaled at the rear a roller *b*. The front ends of the side-bars are connected by the load-support *c* which is adjustably attached to each side-bar by means 35 of the hooks *d*, the upper end of each of which extends through an end of the load-support and is held in place by a nut *e*. In the rear of the load-support *c* are journaled in the side-bars *a* two rotatable harrows *f* the 40 teeth *g* of each of which travel in the intervals between teeth of the other harrow. Between the roller *b* and the rear harrow *f* is adjustably mounted upon the side-bars *a* the rear load-support *h* near the middle of which 45 is secured the seat standard *i*. The rear load-support *h* may like the front load-support *c* be moved along the side-bars *a* so as to adjust the point of application of the load. The load-supports are adapted to carry 50 rocks, stone and the like by which the device is suitably weighted for the purpose in view.

The whole device is hauled along the ground by means of draft devices *j* which are attached to the front load support *c*.

The device is very simple in construction 55 and the parts are so arranged with reference to the side-bars *a* that they may be quickly assembled and may be easily taken apart for repair or for the substitution of broken or worn parts by new parts. 60

I claim:

1. A combined harrow and roller consisting of a pair of side-bars; a roller journaled in said side-bars at one end thereof; a load-support adapted to carry rocks, stone and the like and attached at each of its ends to one of said side-bars at the other end thereof; a second load-support attached to said side-bars in front of said roller; and a pair of harrows journaled in said side-bars between said 70 load-supports.

2. A combined harrow and roller consisting of a pair of side-bars; a roller journaled in said side-bars at one end thereof; a load-support adapted to carry rocks, stone and the like and attached at each of its ends adjustably to one of said side-bars at the other end thereof; draft devices attached to said load support; a second load support adjustably attached to said side-bars in front of said 80 roller; and harrow devices journaled in said side-bars between said load-supports.

3. A combined harrow and roller consisting of a pair of side-bars; a load-support adapted to carry rocks, stone and the like 85 and attached to said side-bars; a roller journaled in said side-bars; a second load-support attached to said side-bars between said roller and the first-named load-support and free to be shifted along said side-bars; and 90 harrow devices between said load-supports, said devices being journaled in said side-bars.

In witness whereof I have hereunto set my hand this twenty sixth day of November 95 A. D. 1907 at said Medina in the presence of the two undersigned witnesses.

ALVIN HAYES.
